UNITED STATES PATENT OFFICE.

DAVID RAYMOND MONTGOMERY, OF WILMINGTON, DELAWARE.

ICE-CREAM CONTAINER.

1,180,868.

Specification of Letters Patent. Patented Apr. 25, 1916.

Application filed September 21, 1914. Serial No. 862,685.

To all whom it may concern:

Be it known that I, DAVID RAYMOND MONTGOMERY, a citizen of the United States, residing at Wilmington, in the county of 5 New Castle and State of Delaware, have invented certain new and useful Improvements in Ice-Cream Containers, of which the following is a specification.

My invention relates to improvements in 10 ice cream containers, the object of the invention being to provide a receptacle for ice cream and other similar material which will dispense with the use of ice or other refrigerating medium, utilizing in lieu thereof a 15 vacuum space between an inner and an outer shell, and provide in the inner shell improved means for permitting the melted cream which forms at the top to flow downwardly into a space below the false bottom 20 supporting the cream.

A further object is to provide a container of the character stated which comprises a body and a cover both having a vacuum space, and provide between the inner and 25 outer shells of the body improved means for holding the shells against collapse, and insuring a strong and rigid construction.

A further object is to provide a container of the character stated which is neat and attractive in appearance, and strong and durable in use.

With these and other objects in view, the invention consists in certain novel features of construction and combinations and arrangements of parts as will be more fully hereinafter described and pointed out in the claim.

In the accompanying drawings: Figure 1 is a view in vertical longitudinal section 40 illustrating my improved container. Fig. 2 is a top plan view, and Fig. 3 is a view in transverse section on the line 3—3 of Fig. 1, parts being broken away.

1 represents an inner shell, and 2 an outer 45 shell forming the body of my improved container. These shells 1 and 2 are preferably of metal, and are of the same general shape except that the inner shell is appreciably smaller than the outer shell, so that a vacuum space 3 is provided between the shells. A spacing ring 4 is located in the vacuum space between the inner and outer shells adjacent their upper ends, and this ring is preferably perforated as shown for lightness, 50 yet is of sufficient strength to prevent collapse of the body.

To the bottom of the inner shell 1, I secure brackets 5, preferably by welding, although of course, I am not limited to the particular manner of connecting the parts. 60 These brackets 5 have their base portions 6 supported on the bottom of the outer shell 3, and are located between lugs 7 formed on the outer shell.

As the shells are preferably joined at the 65 point 8, where their edges are slightly overlapped and welded or otherwise permanently connected, the brackets 5 can be secured to the inner shell 1 before the parts are assembled, and when the inner shell is placed in 70 the outer shell, the brackets will be guided into place inside the lugs 7, and firmly hold the parts against possibility of collapse.

The outer shell 3 is preferably inclosed in a casing 9. This casing 9 is preferably of 75 wood, strengthened by hoops or bands 10.

While I have shown my improvements of 80 general rectangular form, it is to be understood that I am not limited in this particular.

The sides of the casing 9, at their upper ends, are preferably provided with inwardly projecting flanges 11 which overlie the upper edge of the outer shell, and the upper end of the inner shell is concaved as shown at 12 85 to form a seat for a gasket or packing ring 13 against which my improved cover 14 is located. The cover 14 fits into the body of the container and is made hollow as shown at 15 to form a vacuum space. On the cover 90 15, I preferably provide a coating 16 of fibrous non-conducting material, and I also preferably make the ring 4 of such fibrous material. The cover 14 is so shaped as to bear against the ring or gasket 13, and is 95 provided on its outer face with a handle 17 secured rigidly thereto. On one end of the handle, a finger 18 is provided which projects through a loop 19 on the casing 9, and on the other end of the handle, a pivoted 100 hasp 20 is provided which engages over a staple 21 on the casing, and is adapted to be locked by means of any ordinary padlock or other securing device (not shown).

The shell 1 is provided near its lower end 105 with a removable false bottom 22 supported on lugs 23, projecting inwardly from the inner surface of the shell. To the side of the shell, I secure guide bars 24 spaced apart and supporting a removable perforated 110 drain 25. This drain 25 is curved in cross section, so that it provides a passageway

down which melted ice cream or other liquid can flow into the space below the false bottom 22. To prevent the drain from being forced downwardly too far into the body, I 5 provide lugs 26 on the lower ends of the guides acting as shoulders to limit the downward movement of the drain.

Ice cream when in the container will be maintained at a uniform temperature by 10 means of the partial vacuum within the body and the cover, but in the event any of the cream should melt, the melted cream will form on top of the body of cream, and will pass through the perforated drain 25 down 15 into the space below the false bottom 22, hence there will be no accumulation of the melted cream on top of the frozen cream, and the person dispensing the cream will always find at the top, cream ready for serving. This is particularly desirable where 20 the container is used in soda fountains and other public places where it is necessary to continually remove the cover, and of course the drain is adapted for use at all times, as 25 it prevents melted cream from affecting the body of the cream.

It is to be understood, of course, that the false bottom 22 is provided with a recess 28 at one side to accommodate the drain, and 30 that the drain and the false bottom can both be removed when it is desired to clean the container.

Various slight changes might be made in the general form and arrangement of parts described without departing from my invention, and hence I do not limit myself to the precise details set forth, but consider myself at liberty to make such changes and alterations as fairly fall within the spirit and scope of the appended claim. 35

Having thus described my invention, what I claim as new and desire to secure by Letters Patent is:

A container of the character described, comprising a body and a cover having 45 vacuum spaces therein, a false bottom removably supported in the body and having a recess in one side, parallel guides secured to the inner face of the body and projecting through the recess in the false bottom, a perforated drain located in said guides and extending from a point adjacent the top of the body to a point below the false bottom, and lugs on the lower end of said guides limiting the downward movement of the drain, substantially as described. 50 55

In testimony whereof I have signed my name to this specification in the presence of two subscribing witnesses.

DAVID RAYMOND MONTGOMERY.
